B. V. EDWARDS.

MUSIC ROLL.

APPLICATION FILED JUNE 9, 1913.

1,122,706.

Patented Dec. 29, 1914.

UNITED STATES PATENT OFFICE.

BRUCE V. EDWARDS, OF NEWARK, NEW JERSEY, ASSIGNOR TO EDWARDS ENGINEERING & MANUFACTURING COMPANY, OF NEWARK, NEW JERSEY, A CORPORATION OF NEW JERSEY.

MUSIC-ROLL.

1,122,506.

Specification of Letters Patent. Patented Dec. 29, 1914.

Application filed June 9, 1913. Serial No. 772,512.

To all whom it may concern:

Be it known that I, BRUCE V. EDWARDS, a citizen of the United States, and resident of the city of Newark, county of Essex, and 5 State of New Jersey, have invented certain new and useful Improvements in Music-Rolls, of which the following is a specification.

My invention relates to music rolls and 10 particularly to the provision of novel means for attaching the end of a sheet to the take-up spool of a player piano. Various forms of devices have been used for this purpose hitherto, but the general practice has been 15 to make use of a metal ring or clip secured to the end of the sheet. There are several disadvantages connected with the use of such metallic fastening means, as, for example, they are likely to scratch or mar the 20 surface of the player piano or other furniture with which they may come in contact, and, when the sheet is rewound, such attaching means rotating freely upon the spool, after the rewinding has been completed, 25 come into contact with the walls of the spool box, and the finish of the spool box is speedily ruined by such contact, and further the contact of the metallic fastener with the interior of the spool box sets up an unpleasant 30 noise or clatter, and even when, as has sometimes been done, a metallic plate is provided for receiving the wear thus created, the enamel or other finish of such plate is marred after considerable use, and the unpleasant 35 nature of the noise or clatter caused by contact of the fastening means with such metallic plate is very much increased.

According to my invention, the fastening means is made from soft material which will 40 not mar the interior of the spool box or the surface of the player piano or any other furniture with which it may come in contact, but which will nevertheless satisfactorily serve all the purposes of an attaching 45 means, and which can be firmly and securely attached to the end of the sheet, so that it cannot readily be detached therefrom, and further the fastening means and the means for securing it to the end of the sheet are 50 substantially continuous and fairly stiff, making it unnecessary to get hold of the fastening means itself, as is necessary with the metallic ring, and the operator by taking hold of the comparatively broad securing 55 device for holding the fastening means in

place can effect the attachment of the music sheet to the spool much more readily than when a metallic ring or loop is used for this purpose.

With the foregoing and related objects in view, my invention consists in the parts, improvements and combinations herein set forth and claimed.

In the accompanying drawing forming a part of this specification, and illustrating 65 the preferred embodiment of my invention, Figure 1 is a view showing the end of the note sheet, the attaching means, and the means for securing the attaching means to the end of the note sheet, before assembly; 70 Fig. 2 is a plan view showing the back of the note sheet end after the parts have been assembled; Fig. 3 is a sectional view taken on the line 3—3, Fig. 2, and Fig. 4 is a top view on a reduced scale of the completed 75 structure.

Reference numeral 1 is applied to the note sheet, the end of which is trimmed in the customary manner with the margins 2, 3 being cut as is usual at an angle of 45 degrees or 80 thereabout to the sides of the note sheet, and leaving the short square end 4 at the center.

5 designates a section of preferably woven material such as tape, which may be of any convenient width, and of a length dependent upon its width, but sufficient to permit its being bent up at the ends and to form a securing means as hereinafter described. This member 5 of tape or like material has a coating 6 of glue or cement or like material applied thereto on one surface, and such material may either be freshly applied 90 at the time of assembly of the parts, or it may be applied to the tape or like material and permitted to harden before the latter is 95 cut into lengths, and afterward softened by the application of a suitable softening agent at the time of the assembly of the parts.

Reference numeral 7 is applied to the attaching means proper, which, as stated, is 100 of a soft material and may be a piece of ordinary cord, and it may be circular in cross section, as such cord is customarily manufactured, or it may have any desired form of cross section.

In assembling the parts, the securing means 5, with freshly applied or previously applied and softened cementitious material 6 thereon, is placed across the end of the music roll sheet 1, the edge thereof registering 110

or substantially registering with the extreme end 4 of the sheet 1, and the projecting corners 8 and 9 thereof are bent along the marginal lines 2 and 3 of the sheet 1 backward 5 upon the reverse side of the sheet 1, the portions 11, 11 of the cord or other attaching material 7 being inserted along the marginal lines 2 and 3 of the sheet and between the material of the sheet 1 and the bent over end 10 portions 8 and 9 of the securing means 5, as is clearly shown in Fig. 2. Additional glue or other cementing material may be applied, if desired, but ordinarily the coating 6 applied to the securing means 5 will be ample. 15 The parts having been arranged in this position, are subjected to pressure in a suitable press, thus firmly securing together the sheet 1, securing means 5, the tabs or turned over portions 8 and 9 thereof and the portions 20 11, 11 of the attaching means 7 and also resulting in flattening out and broadening the sections 11, 11 of the cord or other attaching means 7 and making a thin flat structure of great strength. The loop 10 25 formed in the cord or other attaching means 7 is permitted to project centrally beyond the end of the note sheet and the securing means, and by means of this loop the end of the note sheet can be readily and 30 conveniently attached to the hook of the takeup spool, or suitable means can be applied thereto for holding the roll in its rolled up condition, and it will be seen that the entire structure, while sufficiently flexible for 35 all purposes, is nevertheless somewhat stiff and the operator by grasping the end of the sheet 1, reinforced in the manner described, can readily and conveniently place the loop 10 over the hook or other attaching means 40 upon the takeup spool.

While I have illustrated the preferred embodiment of my invention, it is to be understood that the precise form shown is for purposes of illustration only and that 45 changes may be made within the scope of my claims without departing from my invention or sacrificing any of its advantages.

I claim as my invention:

1. In a music roll, the combination of a 50 sheet having its ends cut away at the sides at substantially equal angles, an attaching means of soft material, and means for secur-

ing said attaching means to said sheet extending across the end thereof and folded over to embrace both faces thereof, substantially as and for the purposes set forth. 55

2. In a music roll, the combination of a sheet having its ends cut away at the sides at substantially equal angles, a section of soft material disposed along the cutaway 60 edges and projecting to form a central loop, and means for securing said soft material to said sheet along the edges thereof, substantially as and for the purposes set forth.

3. In a music roll, the combination of a sheet having its ends cut away at the sides at substantially equal angles, a cord extending along the cutaway edges of said sheet and projecting beyond the end thereof, and securing means infolding said cord and the 70 end of said sheet, the portion of said cord so infolded being flattened out, substantially as and for the purposes set forth. 65

4. In a music roll, the combination of a sheet having its ends cut away at the sides 75 at substantially equal angles, a section of soft cord disposed along a portion of said cutaway edges at the back of said sheet, and projecting centrally to form a loop, and reinforcing means extending across the end of 80 said sheet and bent over at the rear face thereof to inclose the said cord, all of said parts being firmly cemented together, substantially as and for the purposes set forth.

5. In a music roll, the combination of a sheet having its end cut away at the corners 85 at substantially equal angles and cut square across at the extreme end, a section of soft cord disposed along a portion of said cutaway edges at the back of said sheet, and 90 projecting centrally to form a loop between the cord and the square cut end portion, and a strip of tape extending across the end of the sheet in front and bent over at the rear face thereof to inclose said cord, all of said 95 parts being firmly cemented together, substantially as and for the purposes set forth.

In witness whereof I have hereunto signed my name in the presence of two subscribing witnesses this 6th day of June, 1913. 100

BRUCE V. EDWARDS.
